UNITED STATES PATENT OFFICE.

JOSE CASTILLO PERAZA, OF NEW YORK, N.Y.

INTERNAL-COMBUSTION ENGINE.

Application filed March 24, 1921. Serial No. 455,310.

To all whom it may concern:

Be it known that I, JOSE CASTILLO PERAZA, a citizen of the Republic of Mexico, residing at and whose post-office address is 5 285 St. Nicholas Avenue, in the city of New York, county and State of New York, have invented certain new and useful Improvements in Internal-Combustion Engines; and I do hereby declare the following to be a 10 full, clear, and exact description of the invention, such as will enable others skilled in the art to which it appertains to make and use the same.

The invention relates to internal combustion engines of the type involving a rotary sleeve valve within the cylinder and within 15 which the piston operates, and the object of the invention is to provide a simplified and efficient structure including means for 20 effecting pressure-tight joints between the sleeve valve and the cooperating parts of the engine structure to prevent leakage of the explosive charge undergoing compression and also of the exploded charge, there- 25 by avoiding the loss of power which such leakage would entail.

The invention is illustrated in the accompanying drawings, in which:—

Fig. 1 is a fragmentary plan view of the 30 top casting of an engine;

Fig. 2 is a fragmentary vertical elevation on line 2—2 of Fig. 1;

Fig. 3 is a similar view on line 3—3 of 35 Fig. 1;

Fig. 4 is a horizontal section on line 4—4 of Fig. 3;

Fig. 5 is a perspective view of a section 40 of the packing means, including an adjustable packing bar and a cooperating packing ring;

Fig. 6 is a perspective view of another packing ring;

Fig. 7 is a plan view of the engine with 45 the top casting removed; and

Fig. 8 is a fragmentary sectional elevation on line 8—8 of Fig. 7.

Referring to the drawings, 1 indicates the block or cylinder casting, which may involve a single cylinder or multiple cylinders, 50 which is preferably provided with the usual water jacket for cooling purposes, said casting being provided with a peripheral flange 2 to which the top casting 3 is secured by the usual bolts. As illustrated, the engine 55 is provided with four cylinders, each of which has an annular enlargement 4 near

the top thereof connected to the body of the cylinder by an inclined wall 1', which constitutes an abutment for a correspondingly inclined shoulder on the cooperating sleeve valve, to be more particularly described hereinafter. The upper end of the main casting above the cylinders is recessed to receive the flanges on the upper edges of the sleeve valves. 65

Fitting within each of the cylinders 1 is a rotary sleeve valve 11 which is provided with combined inlet and exhaust ports 16 located on opposite sides of the cylinder and with auxiliary exhaust ports 16', such as 70 commonly employed in engines of this type. The interior of each of the sleeve valves is accurately bored to receive the cooperating piston, not shown, and near the upper end of each sleeve valve there is provided an 75 enlargement fitting the annular enlargement 4 of the corresponding cylinder. Between the annular enlargement of the valve and the main body portion thereof is an inclined shoulder 12, which abuts the corresponding 80 shoulder 1' on the interior of the cylinder wall, the abutting annular shoulders serving as a ground joint to prevent leakage of pressure between the sleeve valve and the cylinder wall. The extreme upper edge of each 85 sleeve valve is provided with a toothed flange 13 by means of which the valve is rotated in the cylinder and which also serves to impart rotary motion to the next valve. A packing ring 14 is applied to a peripheral 90 groove just below the flange 13 and engages the inner wall of the cylinder. Connected to the inner face of the top casting, in alignment with each sleeve valve and accurately fitting the latter, is a disc 3', which disc is 95 provided with a peripheral packing ring 5 engaging the inner wall of the sleeve valve. The discs 3' are secured to the top casting by suitable bolts 7 and both the top casting 3 and the several discs 3' are provided with 100 central aligning openings 8 and 8' adapted to receive the usual spark plugs.

The inner peripheral upper edge of each of the sleeve valves 11 is provided with a bevel 15 adapted to receive a correspondingly bevelled packing ring 17 located in a recess 16 in the top casting 3, which packing ring is held firmly to its seat 15 by pins 18 mounted in hollow bosses 19 formed on the top casting 3 and acted upon by 110 helical springs 20, the tension of which is adjusted by means of cap nuts 21 in screw

threaded adjustment with the said bosses 19, which packing ring 17 not only serves as a means for preventing leakage past the upper inner edge of the sleeve valve, but 5 also serves as a means for forcing the inclined annular shoulder 12 on the sleeve valve into tight engagement with the corresponding inclined shoulder 1' on the inner wall of the cylinder, and also admits 10 of a ready adjustment of the sleeve valve in a longitudinal direction to compensate for wear between the shoulders 1' and 12.

In order to prevent any leakage in a peripheral direction between the sleeve valve 15 and the cylinder in which the same operates, the upper end of each cylinder wall is provided with a peripheral series of pockets 30, each pocket receiving a vertical packing bar 31, the inner face of which bears against 20 the outer wall of the valve, and the rear face of which is provided with a cam 32 adapted to be engaged by a cam nose 35 on the end of an adjustable bolt 34, the upper end of which passes through an opening 25 in the top casting 3 and is suspended by a helical spring 38 mounted in a hollow boss 36, which spring bears upon a cap 37 adjustably secured to the end of the rod 34, the construction and operation of the parts 30 being such that the bars 32 are forced 35 against the outer surface of the sleeve valve with a yielding pressure, which may be regulated by adjusting the tension of the springs 38 by means of the nuts 37', as will be understood. The upper end of each bar 31 is provided with an angular nose 33 adapted to engage a notch or recess 33' in packing ring 14 in the outer face of the sleeve valve, thereby retaining the packing 40 ring 14 stationary while the sleeve valve, to which it is applied, revolves.

The toothed flanges 13 on adjacent pairs of the sleeve valves 11 are in engagement with each other, and between the intermediate valves 11 there is provided an idler gear 42 meshing with the toothed flanges on the adjacent valves, to complete the gear train for operating all of the valves at the same speed and in the same timed relation. 45 The several gears of the train are driven by means of a pinion 40 mounted upon a vertical shaft 41, which is driven from the crank shaft. The entire gear train is housed within the recess formed between 50 the top casting 3 and the top of the cylinder casting, as illustrated in Figs. 7 and 8. Preferably the shaft of the connecting idler gear 42 is extended through the top casting and is provided with a distributor or 55 rotary switch controlling the ignition, conventionally illustrated at 44 in Fig. 8.

From the foregoing description it will be apparent that the several sleeve valves are effectively guarded against leakage of pressure in a longitudinal direction, by reason

of the joints formed by the 45° bevelled shoulders 1' and 12 on the inner walls of the cylinders and the outer faces of the valves, which bevelled shoulders are maintained in accurate gas-tight engagement by means of the adjustable bevelled edge packing rings 17 engaging the upper bevelled edges of the several valves, and against leakage in a peripheral direction by the vertical packing bars 31, which are held in firm but yielding contact with the outer faces of the valves by the special means provided for this purpose.

What I claim is:

1. An internal combustion engine comprising a cylinder having a peripheral enlargement toward its top terminating in a bevelled shoulder, a sleeve valve mounted for rotation therein having an outer peripheral enlargement engaging the enlargement in the cylinder and a bevelled shoulder coacting with the shoulder on the inner cylinder wall, a bevelled face on the upper rim of the valve, a bevelled ring mounted in the cylinder head engaging said bevelled face, and means for exerting pressure on said bevelled ring to force the bevelled shoulders on the valve and cylinder into engagement. 80

2. An internal combustion engine comprising a cylinder having a peripheral enlargement toward its top terminating in a bevelled shoulder, a sleeve valve mounted for rotation therein having an outer peripheral enlargement engaging the enlargement in the cylinder and a bevelled shoulder coacting with the shoulder on the inner cylinder wall, a bevelled face on the upper rim of the valve, a bevelled ring mounted in the cylinder head engaging said bevelled face, pins in the cylinder head engaging said bevelled ring, and adjustable tension springs acting on said pins to force the bevelled shoulders on the valve and cylinder into engagement. 95

3. An internal combustion engine comprising a cylinder, a sleeve valve mounted for rotation therein, said cylinder and valve having coacting peripheral bevelled shoulders to form a gas-tight joint, means for forcing said shoulders into engagement, vertical packing bars mounted in longitudinal pockets in the inner wall of the cylinder engaging the adjacent face of the sleeve valve, and means for holding said bars in contact with the sleeve valve. 115

4. An internal combustion engine comprising a cylinder, a sleeve valve mounted for rotation therein, said cylinder and valve having coacting peripheral bevelled shoulders to form a gas-tight joint, means for forcing said shoulders into engagement, vertical packing bars mounted in longitudinal pockets in the inner wall of the cylinder engaging the adjacent face of the 120

sleeve valve, and adjustable yielding means for holding said bars in contact with the sleeve valve.

5. An internal combustion engine comprising a cylinder, a sleeve valve mounted for rotation therein, said cylinder and valve having coacting peripheral bevelled shoulders to form a gas-tight joint, means for forcing said shoulders into engagement, vertical packing bars mounted in longitudinal

pockets in the inner wall of the cylinder engaging the adjacent face of the sleeve valve, rods depending from the cylinder head, co-acting cams on the rods and bars to force the latter into engagement with the sleeve ¹⁵ valve, and spring tension means for suspending said rods.

In testimony whereof I affix my signature.

JOSE CASTILLO PERAZA.
